DEODORIZING DEVICE

Bertram Schäfer, Osnabrück, Germany

Application January 8, 1957, Serial No. 633,154

Claims priority, application Germany January 9, 1956

1 Claim. (Cl. 21—108)

This invention relates to air freshening, sweetening, neutralizing, perfuming, sterilizing, moth-proofing, insect repelling or otherwise air treating devices commonly known as "deodorizing" devices.

More particularly stated, this invention relates to deodorizing devices of the air circulating type. In this type the air to be treated passes through a casing adapted to receive the odorizing body.

A known device for insect repelling comprises a pair of telescopic members in rotative relation and adapted to present a series of registering apertures or parts from which the vapors may issue into the surrounding. By turning one of the members the apertures may be closed or opened respectively.

It is a primary object of the invention to provide a deodorizing device which will be most simple in structure, cheap to manufacture, easy to install on any smooth surface without necessitating screws, nails or the like, and which is especially adapted for use in motor vehicles, airplanes or the like wherever mechanically moved air is at hand.

According to the invention this object as well as others are achieved by providing a cylindrical casing which consists of a rear and a front member having telescopingly and rotatively engaging cylinder walls each of which having at least two diametrically opposed apertures adapted to register upon rotation of the front member. Centrally fastened to the rear member there is a suction cup, made of resilient material, such as rubber, polyvinyl ester or the like, which extends with a projection through the rear face wall into the interior of the casing. The centre of this projection is provided with a cavity, serving as the female part of a pushbutton while a central extension of the front casing member serves as the male part of a pushbutton thus holding the casing members resiliently and rotatively together. The central extension of the front casing member is at the same time adapted to receive the deodorizing body.

With these objects in view together with others which will appear as the description proceeds, the invention resides in the novel formation, combination and arrangement of parts all as will be described more fully herein-after, illustrated in the drawing and particularly pointed out in the claim.

In said drawings

Fig. 1 is a longitudinal section of the device being attached to the wind shield of a motor car in front of a ventilating air channel,

Figure 2 is a front view of the device in "open" position,

Figure 3 is the rear casing member viewed towards the inlet opening,

Figure 4 is a plan view of the rear of the suction cup,

Figure 5 is a longitudinal view of the rear casing member showing the manner of attaching the suction cup thereto,

Figure 6 is a longitudinal section of the deodorizing body,

2

Figure 7 is a longitudinal section of the front casing member.

The casing having a circular and relatively flat form is preferably made of plastic material and consists of a rear and a front member 1 or 2 respectively.

A suction cup 3 known per se made of resilient material such as rubber, plastic material or the like is fastened to the rear member 1 by forcing a flange 4 of the suction cup through a square hole in the face wall 5 of the rear member 1.

A cavity 6 centrally arranged in that part of the suction cup 3 extending into the casing is provided with an annular lip 7 adapted to receive a flangelike head 8 of an extension 9 being centrally arranged and projecting from the inside of the front casing member 2. Near its root the extension 9 is reinforced by ribs 10.

The rear member 1 has a cylindrical wall 11 which is slightly conical on the inside and adapted to receive a cylinder wall 12 of the front casing member 2 being slightly conical on the outside to fit into the rear casing member 1.

An inlet opening for the air to be treated has been arranged in the wall 11 of the rear casing member which is surrounded funnelike on three sides by a projecting wall 14.

An outlet opening 15 is arranged diametrically opposite of the inlet opening 13. Corresponding apertures 16 and 17 have been arranged in the cylinder wall 12 of the front casing member 2.

A mark 18 has been provided at the front side of the wall 14 of the rear casing member. The face wall of the front casing member 2 extends flangelike over the cylinder wall 12 offering a good grip when actuating this part. In the middle plane of the apertures 16 and 17 marks 19 and 20 have been provided near the circumference of the face wall of the front casing member 2 which upon registering with the mark 18 indicate that the apertures 13, 16 and 15, 17 are in line and fully open for the passage of air therethrough. The deodorizing body 22 made of felt, blotting paper or the like is of circular shape having a centre hole 21 adapted to be placed on the extension 9 of the front casing member 2. This deodorizing body may be saturated with perfume, insect repelling fluid or the like.

In open position of the apertures 13, 16, 15, 17 indicated by registration of the marks 18, 19 or 18, 20 respectively the air to be treated passes the interior of the casing coming in contact with the deodorizing body 22 and leaving the casing enriched with vapors of deodorant fluid.

The deodorizing device according to the invention is fastened to the inside of a wind shield 23 by means of suction cup 3 in a manner known per se adjacent to the outlet of an air channel 24.

55 I claim:

In a deodorizing device adapted to hold active material and including a substantially cylindrical open-top receptacle for said material; a cover member telescopingly and rotatably engaging said receptacle; a central opening in the bottom of the receptacle; and at least one aperture each in the contacting cylindrical walls of the receptacle and of the cover member adapted to register upon mutual rotational displacement of said receptacle and said cover member; the improvement comprising connecting or coupling means for said receptacle and said cover member; said connecting or coupling means including a stem made of resilient material and tightly penetrating said central opening in the bottom of the receptacle; a suction cup integral with said stem on one end thereof and located outside the receptacle back to back thereto; a button-like head within the receptacle integral with said stem at the other end thereof and adapted to engage the bottom of

the receptacle and to retain the same in back to back contact with said suction cup; a cavity axially extending into said stem from the inside of the receptacle; an annular lip at the mouth of said cavity extending inwardly thereinto; a bolt-like projection integral with the cover member and centrally extending therefrom towards the said cavity of the stem; and a button-shaped head at the end of said projection adapted to enter said cavity through

the mouth thereof and beyond said annular lip to engage the same.
